NURSING BOTTLE HOLDER

Fred Nickelson, Topeka, Kans.

Application June 21, 1944, Serial No. 541,316

2 Claims. (CL. 248—103)

This invention relates to nursing bottle holders, and more particularly to such a holder adapted to be supported on a crib, bassinet, high chair or the like, within easy reach of the infant.

A primary object of this invention is the provision of a nursing bottle holder so constructed that an infant may nurse from the bottle without the necessity of the presence of an adult.

An additional object is the provision of such a holder which may be readily adjusted to accommodate a variety of sizes of nursing bottles.

A still further object is the provision of such a holder having means whereby the height of the bottle with respect to the position of the infant, may be suitably varied.

A still further object resides in the provision of such a holder having means serving to retain the various parts in varied positions of adjustment.

Other objects reside in the combinations of elements, arrangements of parts, and features of construction, all as will be more fully pointed out hereinafter, and shown in the accompanying drawings, wherein there is disclosed a preferred embodiment of this inventive concept.

In the drawings:

Figure 1 is a side elevational view of one form of device embodying the instant invention as suspended from a suitable support.

Figure 2 is a top plan view of the device of Figure 1, the nursing bottle disclosed in Figure 1 being omitted.

Figure 3 is a sectional view taken along the line 3—3 of Figure 2, certain parts thereof being broken away, and the nursing bottle being shown in operative position, in dotted lines.

Figure 4 is a sectional view taken along the line 4—4 of Figure 2 as viewed from the right, and

Figure 5 is a sectional view taken along the line 5—5 of Figure 2 as viewed in the direction of the arrows.

Like reference numerals refer to like parts throughout the several views of the drawings.

Having reference now to the drawings there is generally indicated at 10 a nursing bottle holder, adapted, in a manner to be described herein-after, to support a nursing bottle 11 provided with a conventional nipple 12, and be suspended in operative position from any desired support 13.

Bottle holder 10 is comprised of a base, or bottle supporting plate generally indicated at 14, and a backing plate generally indicated at 15. Base plate 14 is comprised of a flat member 16 prefer-

ably formed of suitable sheet metal, the outer edges of which are upwardly and inwardly turned as at 17 to provide, as best shown in Figure 4, a pair of channels 18 at the edges of member 16. An end of member 16 extends a substantial distance beyond the ends of channels 18 and is bent upwardly as at 19 (See Figure 3) to form an extending portion 20 disposed in angular relationship to member 16, portion 20 comprising, in a manner to be described hereinafter, an element of backing plate 15. Slidably mounted in channels 18 is a second member 25 preferably composed of sheet metal or the like, members 25 and 16 comprising the two elements of base plate 14. Member 25 has secured thereto, adjacent its end, a bottle supporting device 26, comprised of a wire member having ends 27 secured to plate 25 and a concave formed bottle supporting surface 28 upturned at right angles with respect to ends 27 and hence positioned in right angular relationship to base plate 14. A pair of eyes 29 are secured to member 25, at an intermediate position, adjacent opposite sides thereof, and are adapted to engage the looped ends 30 of a coil spring 31 adapted to retain bottle 11 in position on base plate 14 in such position that the neck of the bottle rests in concave portion 28 of support 26.

Member 16 is provided with a slot 32 therethrough, extending a substantial distance along the length thereof but terminating short of its ends, through which extends the shank 33 of a stud generally indicated at 34, the upper end of shank 33 being secured to member 25. Stud 34 is provided with a head 35 positioned outwardly with respect to slot 32 whereby the path of travel of member 25 in channels 18 is limited to the length of the slot. Member 25 is, as best shown in Figure 5, provided at an intermediate point with an aperture 35' through which extends one leg 36 of a U-shaped leaf spring generally indicated at 37. The other leg 38 of spring 37 extends along the upper side of plate 25 and is secured in any desired manner, as by soldering, at 39 to the upper surface of member 25, thus providing friction means resisting the tendency of member 25 to slide longitudinally within channels 18, whereby parts 25 and 16 are normally held in the position, with respect to each other, to which they are adjusted.

Having reference now to backing plate 15 it will be seen that the same is comprised of a plate-like member 40 having its outer edges inwardly turned as at 41 to provide a pair of opposed chan-

nels 42 within which extending portion 20 of member 16 is adapted to be fitted in such manner as to slide freely therein. As best shown in Figure 3, the lower ends of channels 42 are pinched as at 43 to preclude disassembly of portion 20 from channels 42. Extending portion 20 is provided, also as best shown in Figure 3, with an aperture 45 therethrough through which extends one end 46 of a leaf spring 47, the other end 48 of which extends along the outer surface of portion 20 and is suitably secured thereto as by soldering. Thus leaf spring 47 serves in a manner similar to that of leaf spring 37 to hold extending portion 20 in any position to which it may be adjusted within channels 42. The upper end of member 40 is bent inwardly to form an angle portion 50 and thence downwardly to form a parallel portion 51, thus providing a hook-shaped extremity whereby the device may be supported or suspended from any desired support 13.

From the foregoing the method of use of the device should now be readily understandable. Bottle 11 is first filled and nipple 12 positioned thereon. Members 16 and 25 are then positioned with respect to each other to form a base of suitable length to accommodate a given size bottle, and bottle 11 is then positioned beneath coil spring 31 which retains the same securely in position on base plate 14, the neck of the bottle being supported in concave portion 28 of supporting member 26. Extension 20 is then adjusted in channels 42 in such manner that base plate 14 is at a suitable height.

The hook-shaped extremity of the backing plate is then positioned over a suitable support such as the top rail of a bassinet or a crib, and the device is then in position for use by the infant.

From the foregoing it will now be seen that there is herein provided a device accomplishing all the objects of this invention and many others including advantages of great practical and commercial utility.

As many embodiments may be made of this inventive concept and as many modifications may be made in the embodiment herein shown and described, it is to be understood that all matter hereinbefore set forth or shown in the accompanying drawings is to be interpreted merely as illustrative and not in a limiting sense.

I claim:

1. In a device for holding a nursing bottle, a base plate comprised of a member having its outer edges inwardly turned to provide channels, and a second member slidably mounted in said channels, resilient means, comprised of a leaf spring secured to said second-mentioned

member and bearing on the surface of said first-mentioned member to present frictional resistance to the sliding of said second member in said channel, additional resilient means comprised of a coil spring secured to said second member for securing said bottle to said base plate, a backing plate comprised of a member having its outer edges inwardly turned to form channels and a member comprising an angularly disposed extension of said first-mentioned base plate member slidably mounted in said channels, whereby the position of said base plate with respect to the length of said backing plate may be varied, resilient means, comprised of a leaf spring secured to said angularly disposed extension and bearing on the surface of said first-mentioned backing plate member to present frictional resistance to the sliding of said angularly disposed extension in said channels of said first-mentioned backing plate member, and means comprising a hook-shaped portion at the extremity of said first-mentioned backing plate member for suspending the device from a suitable support.

2. In a device for holding a nursing bottle, a base plate, comprised of a member having its outer edges inwardly turned to provide channels and a second member slidably mounted in said channels, resilient means comprised of a leaf spring secured to said second-mentioned member and bearing on the surface of said first-mentioned member to present frictional resistance to the sliding of said second member in said channels, additional resilient means secured to said second member for securing said bottle to said base plate, a backing plate comprised of a member having its outer edges inwardly turned to form channels and a member comprising an angularly disposed extension of said first-mentioned base plate member slidably mounted in said channels, whereby the position of said base plate with respect to the length of said backing plate may be varied, a third resilient means, comprised of a leaf spring secured to said angularly disposed extension and bearing on the surface of said first-mentioned backing plate member to present frictional resistance to the sliding of said angularly disposed extension in said last-mentioned channels, stop means precluding the complete disengagement of said two base plate members, additional stop means precluding complete disengagement of said two backing plate members, and means comprising a hook-shaped extremity of said first-mentioned backing plate member for suspending the device from a suitable support.

FRED NICKELSON.
